STIFFENING FOR CORSETS.

No. 373,720.

Patented Nov. 22, 1887.

UNITED STATES PATENT OFFICE.

EDWARD B. CADY, OF JACKSON, MICHIGAN.

STIFFENING FOR CORSETS.

SPECIFICATION forming part of Letters Patent No. 373,720, dated November 22, 1887.

Application filed February 24, 1887. Serial No. 223,768. (No model.)

To all whom it may concern:

Be it known that I, EDWARD B. CADY, a citizen of the United States, residing at Jackson, in the county of Jackson and State of Michigan, have invented certain new and useful Improvements in Stiffening Fabrics for Corsets, of which the following is a specification, reference being had therein to the accompanying drawings.

- 10 Figure 1 is a face view of a sheet or web of the stiffening fabric which I provide for corsets. Fig. 2 is a section on the line $x\ x$, Fig. 1. Fig. 3 shows a piece of the fabric after it has been severed from the web. Fig. 4 shows 15 a part of a corset having two or more of the sections or batteries of stiffening-material applied thereto. Fig. 5 shows part of that illustrated in Fig. 4, on a larger scale, some parts being cut away. Fig. 6 is a section on line $x'\ x'$, Fig. 5. Figs. 7 and 8 show one of the stiffening-cords, Fig. 8 illustrating it after it has been wrapped with thread and Fig. 7 showing the relations of the filaments before the wrapping and the binding. Fig. 9 is a vertical 25 section on the line $y\ y$, Fig. 5. Fig. 10 shows one of the stiffening-cords detached, and illustrates the manner of beveling the filaments at the top and bottom of the corset—that is, reducing their ends in number or in thickness. 30 In the drawings, A represents a small bundle of the filaments or fibers of sisal, reed, rattan, whalebone, or feather-bone, or other equivalent material. Some of the materials enumerated—such as sisal—have fibers or filaments which are comparatively long, and suitable cords can be made thereof by winding or twisting together a sufficient number of the filaments, and the cords can be stiffened, if necessary, by applying glue or cement to them; 35 but of some of the others—such as horn, whalebone, or feather-bone—the pieces are smaller and shorter, yet these can be also readily formed into cords by arranging them so as to produce small bunches or bundles and wrapping cords or threads around them, as shown at aa , whereby the filaments can be held snugly together, and in addition to the cords or threads glue or cement also may be employed. 40 In order to produce the fabric which it is desired to make, I take two strips of cloth (drilling, jean, or other equivalent material) and between them insert the stiffening-cords, above

referred to, made of feather-bone or the like material. Each cord of the latter is stitched in place and held separate from the adjacent one. This process can be continued indefinitely—that is to say, one continuous length of the fabric can be produced of any desired width.

The strips of feather-bone, sisal, or other material operate as cording, but are superior to the ordinary cording in many respects, especially when the fabric is to be applied for the purposes here specially aimed at.

In Fig. 7 there is shown a section of one of the cords, formed by packing or twisting together the filaments of feather-bone or other material; and in Fig. 8 the same is shown in conjunction with the binding-thread wrapped around it.

Figs. 1 and 2 show the web or sheet of corded fabric, one layer of cloth being indicated by c and the other by c' . These are stitched together by the sewing-machine, one row of stitches being shown at c^2 and two rows at c^3 . After the fabric has been formed into a web or sheet in the way described, sections can be cut therefrom, as shown in Figs. 2 and 3, and the cutting can be effected to advantage where the aforesaid double rows of stitches c^3 are formed. After the sections have been cut from the web, and also cut to be of the length desired, they are each reduced in thickness at the ends by cutting away one side, as shown at a' , Figs. 3, 9, and 10, this reducing being effected either by reducing the thickness or the number of the filaments of the feather-bone or other material, and, as a result, the strips of cording are made more flexible at the ends, and the cutting of the cloth (either the layers c or c' or that of the corset) is obviated.

In Figs. 4, 5, 6, and 9, is shown the method of applying one of these sections to the corset. D represents the main layer of drilling or the material of which the corset is composed. Upon this the sections C of stiffening material are placed, they being shown in Figs. 4 and 9 as extending from the top edge to the bottom. Over each is placed a covering-piece, E. The edges of this are turned in, as shown at e^2 , and a selvage provided at the edges e^3 . Both the covering-piece E and the stiffening-piece C are outside and independent of the cloth, D, forming the body of the corset. Af-

ter they have been put in proper position relative to the parts D, they are applied to a sewing-machine, and rows of stitches are formed through the selvages of the part E and through 5 the edges of the part C, as shown at e, and also rows of stitches at e' between the stiffening-cords. Then the binding d is applied along the top edge and the bottom of the corset, this being readily sewed in place and saved from 10 cutting and injury by reason of the aforesaid beveling or reducing of the ends of the stiffening-cord.

I am aware of the fact that heretofore corset stiffeners have been formed of strips or fragments of whalebone secured together by a binding-thread, as shown in earlier patents, 15 and I do not claim, broadly, such a stiffening material as my invention.

I am also aware of the fact that a stiffening 20 material has been made by pasting or gluing narrow strips of bamboo between two layers of cloth, and also stitching bamboo in place, the batteries thus formed in either case being inserted between the two main thicknesses of the 25 corset body, and being of uniform thickness from end to end in respect to the stiffening material, and I do not wish to be understood as claiming any of the materials of the character referred to; but I believe myself to be 30 the first to have devised the stiffening sections or batteries herein shown and described, and the manner set forth for applying them. The packed and wrapped cords which I employ will yield—that is, are flexible in all directions— 35 and at the same time are sufficiently elastic to hold the corset properly in position. By employing the external cover-piece, E, I can dispense with the second layer or thickness of

cloth ordinarily employed for the body of the corset, such second thickness being a real advantage only in so far as it acts to hold the stiffening-sections in place. 40

The cords A are substantially round in cross-section, and the filaments thereof are very small and twisted spirally somewhat relatively 45 to the line of the cord as a whole. This increases their elasticity without destroying any of their flexibility, and the wrapping-thread a holds the parts firmly together.

What I claim is—

1. The herein-described composite stiffening fabric for the body of a corset, it comprising two layers of cloth and a series of flexible stiffening-cords, each cord being substantially round in cross-section and formed of small filaments of feather-bone or equivalent material, and each being beveled or partially cut away at the ends of the section of fabric, substantially as and for the purposes set forth. 55

2. In a corset, the combination, with the main layer of cloth, D, of the section of stiffening fabric C, having cords of small filaments of feather-bone or equivalent material extending from the top edge to the bottom of the corset, the cords of said section being beveled or partially cut away at the ends and being secured by stitches between two layers of cloth, the outer covering, E, and the binding d, placed over the ends of the said stiffening-cords and secured by stitches thereto, substantially as set forth. 60 65

In testimony whereof I affix my signature in presence of two witnesses.

EDWARD B. CADY.
